UNITED STATES PATENT OFFICE.

WALTER E. EVERITT, OF SEATTLE, WASHINGTON, ASSIGNOR TO FIREKING FIRE EXTINGUISHER COMPANY INC., OF SEATTLE, WASHINGTON, A CORPORATION OF WASHINGTON.

FIRE EXTINGUISHER.

Application filed September 22, 1926, Serial No. 136,999, and in Canada April 19, 1927.

This invention relates to a fire extinguisher.

An object of the invention is to provide a simple and effective fire extinguisher adapted to spray powder over a flame. The various features of novelty and invention will appear from the detailed description taken in connection with the accompanying sheet of drawings forming part of this application.

10 An embodiment of the invention is illustrated in the drawings, in which—

Fig. 1 is a longitudinal sectional view through the extinguisher;

Fig. 2 is a top plan view taken on line 15 2—2 of the Fig. 1.

Fig. 3 is a detailed sectional view taken on line 3—3 of Fig. 1; and

Fig. 4 is a detailed sectional view taken on line 4—4 of Fig. 1.

20 In the drawings, 1 indicates a container adapted to hold the powder to be sprayed, and 2 a cap on the bottom thereof for closing the opening through which the powder is inserted into the container. A cylinder 3

25 extends into the container and has a piston 4 arranged therein. This piston 4 is preferably formed of cup leather and is backed by a circular plate 5. The piston is mounted on an operating rod 6 being held thereon between nuts 7 and 8 threadedly arranged upon the said rod. A spring 9 is arranged within the piston 4 so that one end is attached to the operating rod 6, while the major portion of the spring bears against the inner circumference of the piston. This arrangement is clearly shown in Fig. 3 of the drawing. As the cup leather piston 4 is apt to shrink and contract during non-use, the spring insures constant engagement between the said piston and the container 3, thus providing at all

35 times an efficient airtight piston within the cylinder.

40 The cylinder 3 projects a short distance beyond the upper end of the container 1, such projecting end being provided with exterior screw threads 10. An interiorly threaded cap 11 is adapted to close the upper end of the cylinder. The cylinder is connected to the container at the point where the former

45 projects through the latter by any suitable connecting means such as by welding or soldering. The operating rod 6 passes through a centrally formed opening in the cap 11. The inner end of the cylinder 3 has an open

cone shaped end 12, while surrounding said cone shaped end is a funnel-like member 13 which extends through the adjacent end of the container 1 being secured thereto in any suitable manner as indicated at 14. The funnel shaped member is corrugated as shown in Fig. 4, such corrugations serving to space the members 12 and 13 so as to allow the powder to pass between the same. The funnel shaped member 13 is provided with a tapered seat 15 adapted to form a seat for a closure member 16 secured to the end of the operating rod 6. This closure member 16 may be threadedly attached to the said rod, or it may be attached in any desired manner.

55 A coil spring 17 is arranged upon the operating rod 6 between the closure member 16 and the nut 8. This spring tends to prevent the closure member 16 from contracting or relaxing from long non-use and allow the powder to escape.

60 The operating rod 6 is provided with a pair of projecting lugs 18 and 19, said lugs extending from the rod in opposite directions. These lugs are adapted to pass through oppositely extending slots 20 and 21 in the cap 11. It will thus be seen that when the extinguisher is not being used the operating rod 6 is turned so that the lugs 18 and 19 will pass through the openings 20 and 21 in the cap; after which a slight turning 65 of the rod will cause the same to remain in such position and the closure 16 to be firmly seated against the seat 15.

70 Suitable openings 28 in the sides of the funnel are provided for the purpose of providing a passage for the powder.

75 An operating handle 22 is threadedly attached to the upper end of the rod 6. This handle has a downwardly projecting base portion 23 which is provided with a hollow tubular part 24. A coil spring 25 is arranged upon the rod 6 within the hollow part 24 of the base, said spring bearing against the upper end of the hollow part and a rubber gasket 26 at the other end. This 80 spring will press the rubber gasket firmly over the opening in the cap when the extinguisher is not being used and the parts are in position shown in Fig. 1. A projecting eye member 27 is formed integral with 85 the upper end of the container 1. The extinguisher may be hung to a nail or other holding means by this eye member.

From the foregoing description it will be apparent that the fire extinguisher described therein will not deteriorate from non-use as the closure member and piston member are provided with means for compensating for any shrinkage or contraction. Also because of the spring within the handle and the rubber gasket against which the same bears, provision is made for keeping openings closed and the air out of the container during non-use of the same.

Having described an embodiment of the invention, the following claims are appended hereto, it being understood, however, that the invention is susceptible of many variations and adaptations within the scope of the said claims.

What I claim is:

1. A fire extinguisher for spraying powder, comprising a container, a funnel within said container having its discharge end projecting through the wall of the container, a cylinder in said container having a conical discharge end extending into said funnel, said funnel being corrugated so as to maintain spaced relation with said conical end, a piston within said cylinder, a piston rod for operating said piston, means movable with said piston for closing the discharge opening in the funnel, and means be-

tween said discharge closing means and said piston for pressing said discharge closing means firmly against the discharge opening, consisting of a coil spring member arranged upon the operating rod between the discharge closing means and the piston, the spring being held in operating alignment by means of the piston rod.

2. A fire extinguisher comprising a container, a cylinder arranged within said container, a piston within said cylinder, an operating rod for operating said piston projecting through the upper end of said cylinder, a handle arranged upon said rod, a gasket mounted on said rod between said handle and the upper end of said cylinder and adapted to seal the opening in the cylinder head through which the rod passes, when said piston is in its innermost position, a spring arranged within said handle and bearing upon said gasket, a pair of oppositely arranged lugs extending from the operating rod at points below said gasket, and slots in the upper end of the cylinder enabling the lugs to be passed through said cylinder end and into locking engagement therewith.

In testimony whereof I affix my signature.

WALTER E. EVERITT.
